UNITED STATES PATENT OFFICE.

WILLIAM E. BAKER, OF ERIE, PENNSYLVANIA.

OIL HEATER.

Application filed July 31, 1924. Serial No. 729,381.

This invention relates to a novel and improved oil heater and has for its primary object to provide an oil heater which will insure complete vaporizing of oil which is to be used in an oil burner.

A further object is to provide a heater employing electric heating means.

Other objects will become apparent during the progress of the description.

10 In the drawings in which I have illustrated a preferred embodiment of my invention,

Fig. 1 is a longitudinal view partly in elevation and partly in section of my improved heater.

15 Fig. 2 is an end elevation thereof looking at the right end in Fig. 1.

Fig. 3 is a section on the line 3—3 of Fig. 1, and

Fig. 4 is a section on the line 4—4 of Fig. 1.

20 Referring to the drawings, 1 is a base of any suitable construction but which I have shown as screw threaded at 2 whereby it may be mounted in a suitable frame or support.

25 Mounted on the base and secured thereto by any suitable means is a tube 3 closed at its outer end 4. Within the tube 3 is a spiral 6

which may be formed in any manner but which I have shown as formed of a coil of wire. This spiral fits immediately within the

30 wall of the tube 3.

Supported on the base 1 in any suitable manner as by being threaded thereto is a sec-

ond tube 7 connecting with a passageway 8 in

35 said base. Surrounding the tube 7 is a sleeve 9 and between the walls of the tube and sleeve

is placed suitable insulating and heat con-

ducting material 10 having a plurality of

bores 11 therein. Placed within these bores

are suitable resistance elements 12 which are

thus insulated from the tube 7 and from the

sleeve 9 as well as from one another. These

resistance elements are preferably connected

in series as shown in Fig. 4 at 13. The resis-

tance elements are provided at the base of the

vaporizer with suitable terminals 14 for con-

nection to any suitable source of electricity.

The base 1 is further provided with a plural-

ity of inlets 15 communicating with an en-

larged opening 16 for the reception of a suit-

able connection to a source of fuel, such as oil.

In operation fuel is admitted through the

inlets 15 into the path formed by the spiral 6,

and passes around the spiral until it reaches

the end 4 of the tube. During this passage

55 of the fuel the resistance elements 12 are

heated and the result is that the fuel is sub-
stantially completely vaporized. The fuel
then flows back through the inner tube 7 and
out of the passageway 8 which may be con-
nected to a suitable conduit leading to a burn-
er.

By providing this circuitous path for the
fuel I insure that ample opportunity is given
for it to become vaporized and heated before
passing to the burner. The plurality of in-

lets 15 separates the fuel to some extent and
spreads it out into a sheet, in which form it en-

ters the spiral path formed by the wire or the
like 6, and therefore presents a large surface
to be heated. The result is that the oil or

other fuel is well vaporized by the time it
reaches the end of the spiral and whatever oil

is not vaporized becomes vaporized on the re-
turn through the inner tube 7. Furthermore,

during this passage through the tube 7 the
entire gas is further heated before passing to

the burner.

60 The employment of electrical heating ele-

ments is very desirable, not only because of
cleanliness but because of the ease with which

the heat may be regulated, for example, by
rheostats and automatic switches. For ex-

ample, I employ this heater with a thermostat
control, as described in my co-pending ap-

lication, Serial No. 735,511, filed September
2, 1924. Moreover, it is a simple matter to
remove and replace any resistance element as

it becomes worn out.

65 From the above description it will be seen
that I have provided a heater which is effi-

cient in operation, which is readily controlled
90 to vary the amount of heat, and which will in-

sure proper vaporization and heating of the
fuel.

I am aware that changes in the form, con-

struction and arrangement of parts may be
made without departing from the spirit and

without sacrificing the advantages of the in-

vention and I reserve the right to make all

such changes as fairly fall within the scope

of the following claims.

100 I claim:—

1. An oil heater comprising a vaporizing
tube, a sleeve within said tube and spaced
therefrom, a fuel inlet between said tube and
sleeve, means for causing the fuel to take a
circuitous path throughout the entire length
of sleeve, a pipe arranged within the sleeve,
a heating element between said pipe and
sleeve, a vapor outlet for said pipe at the end
of the tube where the inlet is located, whereby

the fuel will be in continuous contact with the heating element through its entire travel within the tube.

2. An oil heater comprising a vaporizing tube closed at one end, a plug arranged at the other end, a sleeve within said tube and spaced therefrom and connected to said plug, a pipe in said sleeve and threaded in said plug, a fuel inlet through said plug and having communication with the space between

the tube and sleeve, a spiral between said tube and sleeve for causing said fuel to take a circuitous path through the length of said sleeve, a pipe in said sleeve, a vapor outlet in said plug and communicating with said pipe, and a heating element between said pipe and said sleeve, said fuel being in continuous contact with a heated surface through its entire travel within the tube. 15

WILLIAM E. BAKER.
